UNITED STATES PATENT OFFICE

100,879

DESIGN FOR A CANDY OR LIQUOR BOX

Jack Raisin, Burlingame, Calif.

Application December 6, 1935, Serial No. 59,943

Term of patent 3½ years

To all whom it may concern:

Be it known that Jack Raisin, a citizen of the United States, residing at 1427 Carlos Avenue, Burlingame, in the county of San Mateo and State of California, has invented a new, original, and ornamental Design for a Candy or Liquor Box, of which the following is a specification, reference being had to the accompanying drawing, forming a part thereof:

Fig. 1 is a view in perspective of the candy or liquor box showing my new design.

Fig. 2 is a side elevation.

I claim:

The ornamental design for a candy or liquor box substantially as shown.

JACK RAISIN.
